C. P. GASS

GARMENT HANGER

Filed Oct. 21, 1926

Inventor
C. P. Gass.

By *John Randolph Jr.* Attorney

UNITED STATES PATENT OFFICE

CONRAD P. GASS, OF TACOMA, WASHINGTON.

GARMENT HANGER.

Application filed October 21, 1926. Serial No. 143,172.

The invention relates to a device used for hanging garments, and has for its principal object the provision of a garment hanger that is reasonable in cost of manufacture being made out of a single strand of wire 5 bent to form the hanger, and provided with a coat supporting member, integral upstanding hooks to engage loops on waistbands of nether garments for holding them suspended, and a cross bar that forms a brace and also a suspending means for garments that may be hung thereover.

A further object of the invention is the provision of a garment hanger made of a 15 single strand of wire having its ends twisted together, one of the ends being extended and bent to form a hook for hanging the garment hanger on any desired support, the open frame provided by the twisted ends being formed with outstanding and downwardly extending portions over which the upper 20 garments, such as a coat and vest may be hung, the frame bent under the outstanding and downwardly extending portions to form 25 upstanding hooks adapted to engage belt loops of nether garments, and the hooks connected at their inner ends by means of a cross bar that serves as a brace and also means for suspending the garment.

30 The invention will be described in detail hereinafter and will be found illustrated in the accompanying drawing, in which

Figure 1 is a side view in elevation of the improved garment hanger, and

35 Figure 2, a longitudinal sectional view on a plane indicated by the line 2—2 of Figure 1.

In the drawing similar reference characters will be used to designate corresponding parts in both views.

40 The garment hanger is formed of a single strand of wire of sufficient gauge to make a rigid structure, the wire being twisted as shown at 1 to join the ends of the wire together, one end of the wire being extended 45 and bent to form a hook 2 for suspending the garment hanger from a suitable support. The two ends of the wire are bent outwardly and downwardly as shown at 3 to form a suspending means to be inserted in a coat and vest or the like to suspend them on the hang-

er. The portions of the wire frame at the ends of the part 3 are bent upwardly and inwardly under the part 3 as shown at 4 and then returned as shown at 5 to form elongated, upwardly and inwardly inclined hooks 55 6, said hooks being adapted to engage in the belt loops of a nether garment such as a pair of trousers shown in broken lines at A in Figure 1, the belt loops being designated B. The remainder of the frame forms a cross 60 bar 7 connecting the lower ends of the returned portions 5, said cross bar forming a brace to stiffen the hanger, and is also adapted to be used for suspending a garment by hanging it thereover.

65 It will be apparent that the article is adaptable for domestic use for hanging garments, but is particularly adaptable for use by dealers in clothing, and tailors, and clothes cleaners, as by providing the hooks 6 to suspend trousers by the belt loops, folding of the trousers over a cross bar such as is now practiced is avoided, and the disadvantages incident thereto, that is that the trousers will be creased where hung over the cross bar and 70 are liable to slip therefrom when being carried for delivery, are avoided.

75 It will also be apparent that the hooks 6, by being elongated and upwardly and inwardly inclined, are adapted to hold trousers 80 waistbands of varying lengths, the belt loops on wide trousers sliding down on the hooks until the waist band is fully extended, thus spreading the trousers and preventing wrinkling.

85 What is claimed is:—

A garment hanger formed of a single strand of wire and provided with a cross bar intermediate of its ends, the wire at each end of the cross bar having inwardly and 90 upwardly reentrant portions rebent to form inwardly directed and upwardly inclined hooks for engagement with trousers loops, the wire at the ends of said hooks rebent to form coat supporting portions, and 95 the ends of the wire joined and formed with a suspending hook.

In testimony whereof I affix my signature.

CONRAD P. GASS.
